UNITED STATES PATENT OFFICE

ROBERT A. HOLLAND AND ALFRED H. HOLLAND, OF WINSTON-SALEM, NORTH CAROLINA

EXTENSION TABLE

Application filed October 30, 1931. Serial No. 571,978.

This invention relates to an extension table structure, and more especially to an extension table having the extension structure thereof of all-metal construction, which prevents changes in the dimensions of the parts due to a change in humidity, and insuring easy operation of the extension structure at all times.

Heretofore, it has been customary in many cases to construct extension tables of wood and other materials which changes its form and dimensions according to weather conditions and results in the extension structure being difficult to operate.

On account of the peculiar structure of our device and the all-metal structure thereof, we have provided an extension table which can be manufactured at comparatively low cost and which is positive in its operation at all times and under all types of weather conditions.

Some of the objects of our invention having been stated, other objects will appear as the description proceeds, when taken in connection with the accompanying drawings, in which—

Figure 1 is an elevation of our extension table, extended beyond normal extended position;

Figure 2 is a plan view of the extension structure with the leaves omitted;

Figure 3 is a longitudinal sectional view taken along the line 3—3 in Figure 2;

Figure 4 is a cross-sectional view taken along the line 4—4 in Figure 2;

Figure 5 is a cross-sectional view taken along the line 5—5 in Figure 2, and being on an enlarged scale;

Figure 6 is a view similar to the central portion of Figure 3 but showing a slightly modified construction;

Figure 7 is a cross-sectional view taken along the line 7—7 in Figure 6;

Figure 8 is an enlarged longitudinal sectional view of the left hand corner of the

structure shown in Figure 3; with a modified structure being shown therein;

Figure 9 is an end view of Figure 8, looking from along the line 9—9 in Figure 8;

Figure 10 is a view looking from along the line 10—10 in Figure 2 and showing the means for pivotally and foldably mounting the center leaf of the table.

Referring more particularly to the drawings, 10 and 11 indicate posts for a table, and of course, it is evident that usually two posts 10 are disposed at one end and two posts 11 at the other end. A lower support twelve may be provided. The upper end of the posts 10 and 11 may have a framework there around as is conventional in table structure but in combination with our structure as hereinafter set forth upper supporting means are not necessary because the structure as hereinafter explained is secured to the upper end of posts 10 and 11 as a means of securing the upper ends of posts 10 and 11 together.

Regardless as to whether or not the upper ends of posts 10 and 11 have a frame there around, we secure the strips 13 and 14 to the upper ends of the pairs of posts 10 and 11. A pair of U bars or channel bars 16 and 17 are secured to the members 14 and 15, the U bar 16 being secured by means of brackets 18 and 19 on opposite ends thereof and U bar 17 being secured by means of brackets 20 and 21.

As the structure of the units located on each side of the table are identical a description of one of these U bars and its associated parts will be given and like reference characters with a prime notation, will apply to the other U bar and associated parts.

Each of the U bars has mounted on the inner surface of each outer sidewall portion rollers 22 and 23 and in the central portion thereof also has rollers 24 and 25, the lower rollers 23 and 25 being secured on bolts of 26 which are secured in both of the sidewall portions of the U bar.

Angle member 27 is loosely mounted between the above mentioned rollers and said angle member has a channel formed on the lower edge thereof by the inwardly and upwardly projecting portion 29 and in this channel the upper rollers 22 and 24 are disposed. The lower rollers 23 and 25 support the lower edge of the angle members. These angle members have the upwardly projecting portions formed by indentations 30, 31 and 32 to which is secured the outer leaf, or top section, of the table 34.

In the sidewall portion of angle member 27 is a plurality of perforations forming a rack 36 particularly adapted to engage a toothed wheel, or pinion, 37 mounted on a pin 38, which pin is mounted in an inverted U bracket 39 and also in another U bracket 40 secured to the closed end of U bracket 39, forming a suitable bearing for the pinion 37.

On the other end of U bar 16 is similarly mounted an angle member 41 which is identical in all respects to angle member 27 and is similarly mounted in pairs of rollers 42 and 43 which comprise upper and lower rollers identical to those just described and on these rollers the angle member 41 is mounted in the same manner as described for angle member 27. Angle member 41 has a rack 44 thereon similar to rack 36 and this rack is adapted to engage one side of pinion 37. Angle member 41 has upwardly projecting indentations 45, 46 and 47 to which is secured leaf, or top section, 48.

The U bars 16 and 17 are secured to each other to form a rigid unit by means of braces such as angle members 49 and 50 which are secured in any suitable manner such as riveting or welding to the members 16 and 17.

Pivotedly mounted between the members 49 and 50 is a rod 51 which has two bell cranks 52 and 53 which have holes therein which are penetrated by wood screws 54 and 55, which are embedded in leaf 56, which leaf is in two sections, the other section being indicated by 57, hinged as at 58, and supporting brackets 59 and 60 are secured to the members 49 and 50 for supporting the leaf in folded position. The leaf is adapted to be folded and given a one half revolution to cause it to fall below the plane of leaves 34 and 48 to permit the table to be folded, by pushing the top sections 34 and 48 together.

The above description for one of the U bars and its associated parts fully describes the other U bar and its associated parts and therefore like reference characters will apply to the other U bar with the exception that the other U bar is indicated by reference character 17 but the parts not elsewhere described are indicated by the same reference character with a prime notation associated therewith.

It is evident that when leaf 34 is secured to members 27 and 27' and leaf 48 is secured to members 41 and 41' that a pull on either of

the leaves 34 or 48 will automatically cause the other leaf to move in the opposite direction from that imparted to the leaf engaged by the hand of the person operating the same on account of the reverse motion due to the pinions 37 and 37' engaging the racks 36 and 44 and 36' and 44' to spread the members apart from each other or to cause them to move towards each other.

In Figures 6 and 7, 8 and 9 there is shown a modified form of construction in which the parts are identical to the above described structure except that instead of roller 25 angle bracket 125 is substituted, and instead of the upper roller 22 angle bracket 122 is substituted, the other parts being identical to the structure already described.

It is to be observed that the modified form of construction will operate as easily as the form in which pairs of rollers are provided as the angle members 27 and 27' in the central portions of the U-bars will press upwardly against the rollers, while at the ends of the U-bars the angle members 27 and 27' will press downwardly on the rollers, and therefore, the amount of friction will not be materially increased.

In the drawings and specification there has been set forth a preferred embodiment of our invention, and although specific terms are employed, they are used in a generic and descriptive sense only and not for purposes of limitation, the scope of the invention being set forth in the appended claims:

We claim:

1. An extension table comprising two oppositely slidable outwardly movable top sections, parallel oppositely slidable angle bars secured to the under side of each top section, a pair of U-bars, means for slidably mounting a pair of said angle bars between the sidewalls of said U-bars, each angle bar having a rack therein disposed on that portion of the angle bar which occupies a position between the sidewalls of the U-bar, a pinion mounted on the base portion of each U-bar for engagement with the rack in each side bar.

2. An extension table comprising two oppositely slidable outwardly movable top sections, parallel oppositely slidable angle bars having their horizontal portions secured to the under side of each top section, a pair of U-bars, means for slidably mounting the vertically disposed portion of a pair of said side bars in the sidewalls of said U-bars, each side bar having a rack therein, a pinion mounted on the U-bars and enclosed by the sidewalls of the U-bars for engagement with the rack in each angle bar, means for securing the two U-bars together to form a unit and means for securing said unit to the table frame.

3. An extension table comprising a pair of parallel spaced U-bars, a pair of oppositely extending right angle members having one leg slidably mounted on the sidewalls of each

U-bar, a rack associated with each angle member, a pinion mounted on each U-bar between the angle members for engagement with the rack on each angle member to cause reverse movement between the angle members when one of the angle members has sliding movement imparted thereto, the other leg of the angle members being disposed along the lower surface of a portion of the table top and means for securing the table top to said other leg.

4. An extension table comprising a framework, a table frame, means for securing the framework to the table frame, said framework having two spaced parallel U-bars, a pair of oppositely moving right angle members having one leg thereof mounted on the inner sidewalls of the U-bars, each oppositely moving right angle member having a rack, a pinion mounted between the side walls of the U-bars and having opposed teeth of the pinion engaged by said racks and means for securing a top section of the table to the other leg of each pair of oppositely moving right angle members.

5. An extension table comprising a pair of upwardly opening U-shaped members secured in spaced relation to the top portion of the table, each of said members having two spaced parallel wall portions, a pinion mounted for rotation between the wall portions, oppositely movable right angle members having one leg thereof slidably mounted on said wall portions and each of said movable members having a rack thereon engaging opposed portions of said pinion and means for securing a top section of the table to the other leg of each pair of said movable members.

6. In an extension table, two spaced parallel U-bars, oppositely extending right angle bars slidably mounted on each inner sidewall of each U-bar, a rack on each right angle bar, a pinion mounted on the base of the U-bar between the right angle bars and having opposite portions thereof engaging said racks and a top section secured to a pair of said oppositely extending bars.

7. An extension table having two spaced parallel channel bars, rollers mounted on the sidewalls of said channel bars, a pair of oppositely extending angle bars having a channel on their lower edges engaging the said roller and being slidable with relation to the channel bars, a pinion mounted on the said channel bars, each of said angle bars having a rack engaging said pinion and a top section secured to pairs of angle bars extending in the same direction.

8. An extension table comprising two spaced parallel U-bars, rollers on the sidewalls of said U-bars, angle bars having an upturned lower edge forming a channel in which some of said rollers are disposed, each of the angle bars having racks thereon, a pinion fixedly mounted for rotation on each of said

U-bars and being disposed between the angle bars so the pinion will engage the racks on the angle bars, a top section secured to one of each of the pairs of angle bars and a foldable leaf pivotally mounted between the U-bars and being rotatable when folded to occupy a plane below the plane of the top sections.

In testimony whereof we affix our signatures.

ROBERT A. HOLLAND.
ALFRED H. HOLLAND.
